UNITED STATES PATENT OFFICE.

GEORGE E. AUSTIN, OF NEW YORK, AND FREDERICK A. LACHANCE, OF BROOKLYN,
NEW YORK.

COMMUTATOR-SLOTTER.

1,175,676.

Specification of Letters Patent. Patented Mar. 14, 1916.

Application filed March 22, 1915. Serial No. 16,236.

To all whom it may concern:

Be it known that we, GEORGE E. AUSTIN and FREDERICK A. LACHANCE, citizens of the United States, residing at New York and Brooklyn, respectively, in the counties of New York and Kings, respectively, and State of New York, have invented certain new and useful Improvements in Commutator-Slotters; and we do hereby declare the following to be a full, clear and exact description of the invention, such as will enable others skilled in the art to which it appertains to make and use the same.

This invention relates to commutator slotters for electric motors or generators and more particularly to the removal of the insulating medium between the segments of the commutator of the armatures thereof, as said segments wear down from the friction exerted by the brushes.

An object of this invention is to provide a simplified and compact device which may be carried by the tail-stock of an armature repairing machine common to the trade.

25 A further object of this invention is a provision of a longitudinally movable cutting medium which may follow in line of insulation between the segments.

30 A further object of this invention is an improved means for supporting a movable frame to which a driving medium is attached for driving a cutting medium carried at the end of a swinging frame.

35 A further object of this invention is a provision of an improved means for imparting movement to a sliding carriage which carries the operative parts of this invention.

40 Further objects will be apparent from the following specification, appended claims and drawings in which,

Figure 1 is a side elevation of the device constructed in accordance with this invention, Fig. 2 is an end view thereof, and Fig. 45 3 is a plan view thereof.

It is thought that to those skilled in the art to which this invention appertains, the features of construction will be evident and the following description will clearly define each part together with its association of the other parts.

Referring to the drawings there are shown parts of a tail-stock 10 having the usual hand wheel 11 formed thereon and 55 the lock nut 12 for binding the spindle

therein. To this tail-stock are attached plates 13 as by the screws 14 and these plates have lugs 15 formed thereon to which a frame 16 is attached by having screws 17 pass through the lugs 18 to engage the ends 60 of the lugs 15. A rail 19 is attached to the frame 16 by the screws 20 and this rail is in the form of a T having its upper face machined to form a bed 21 upon which is a carriage 22. This carriage is provided with 65 the plates 23 which retain the carriage upon the bed 21 and the movement of the carriage is limited as by the screw 24 which pass through the lugs 25 formed on the opposite ends of the rail 19.

70 The carriage 22 has ears 26 rising therefrom through which a pin 27 passes to pivotally support a frame comprising the side bars 28, base members 29 and the fitting 30 at the forward end thereof. This 75 frame is pivotally mounted and may be swung to the position shown in dotted lines in Fig. 1 when so desired where it may be locked as by a link 31 which has one end thereof pivotally connected to the carriage 80 22 and its opposite end provided with a boss 32 which engages the extension 33 of one of the side rails 28. A spring 34 normally holds the link 31 in operative position. The fitting 30 is bolted between the side rails 28 85 as at 35 and this fitting has an extension 36 from the bottom face thereof, in which bearings 37 are formed to support an arbor 38. This arbor carries a small circular saw 39 at one end thereof, and a pulley 40 at the 90 opposite end, of which the pulley imparts motion to the arbor and the circular saw 39 serves in the removal of the insulation between the segments of a commutator. As the segments are not always properly aligned 95 with respect to the axis of the armature shaft, it is necessary that the arbor 38 has longitudinal movement to allow the saw 39 to follow the insulation between the segments of the commutator. This is accomplished by having washers 41 yieldably carried by the arbor 38 having movement in one direction only and interposing a spring 42 between the washers to normally establish a fixed position of the saw 39 with respect to the fitting 30. The pulley 40 receives a belt 43 which is driven by a pulley 44 carried by the shaft of a motor 45 which is attached to the base 29.

100 105 110 As it is necessary to maintain the arbor

38 in fixed vertical position when once adjusted to a commutator, the base 29 has an extension 46 formed thereon through which a vertical screw 47 passes and this screw is 5 adapted to have its lower end bear upon a pedestal 48 formed on the carriage 22, while the upper end of said screw supports a hand wheel 49 by which rotation of the screw is had. When the screw has been adjusted to 10 properly position the arbor 38, this screw is clamped in the extension 46 by a screw 50 which is provided with a hand wheel 51 and a collar 52 which binds against one of the extensions of the split socket which receives the screw 47, while the threaded end of the screw 50 engages the opposite portion of the split extension.

When the saw has been properly adjusted with respect to the commutator supported 20 by the spindle of the tail-stock 10, longitudinal movement of the carriage 22 causes this saw to traverse the length of the insulation between the segments and this longitudinal movement is imparted through a 25 series of levers by which the desired throw may be had. Attached to the carriage is one end of a lever 53 which has its opposite end pivoted as at 54 to one end of a link 55 which is pivoted as at 56 to the frame 16. 30 The lever 53 supports a pin 57 upon which a hand wheel 58 is mounted and this pin passes through the slotted portion 59 of a lever 60 so that the hand wheel 58 may clamp the slotted end of the lever 60 at any 35 desired position. The opposite end of the lever 60 is pivoted as at 61 to the hand lever 62 which has its end pivoted as at 63 to the frame 16. It is apparent that after the desired adjustment of the hand wheel is had, 40 manipulation of the hand lever 62 in a swinging direction, proportionate movement is given to the carriage 22 and likewise to the saw 39. Also, when the several parts have been adjusted, it is only necessary to rotate the commutator a fraction of 45 a revolution to bring the successive line of insulation in the path of the saw 39.

Various modifications may be made within the scope of the appended claims 50 without departing from the spirit of the invention and the drawings are submitted for illustrative purposes only.

Having thus described this invention, we claim:—

55 1. In a commutator slotter of the class described, a frame, a bed carried by said frame, a carriage slideable longitudinally on said bed, a supplemental frame pivotally mounted upon said carriage, a cutter carried 60 by said supplemental frame, said supplemental frame having vertical adjustment

with respect to said carriage and a series of levers carried by said frame and carriage for imparting longitudinal movement to said carriage, said levers including a lever 65 having one end thereof pivoted to said carriage, its opposite end movably carried by said frame, a hand lever pivoted to said frame, and a link connecting said hand lever with said first mentioned lever, a connection 70 between said link and said first mentioned lever being adjustable.

2. In a commutator slotter of the class described, a frame, a second frame movably secured to said first mentioned frame, 75 a bed formed on said second mentioned frame, a carriage slidably mounted on said bed, a vertically pivoted supplemental frame carried by said carriage, said supplemental frame supporting a prime mover, an 80 arbor journaled in said supplemental frame, said arbor having longitudinal movement in said frame, a cutter carried by said arbor being adapted to move with said arbor laterally in following the lines of insulation 85 in a commutator, a link pivotally secured to said carriage and yieldably secured to said second mentioned frame and a hand lever carried by said second mentioned frame having adjustable connection with 90 said link.

3. In a commutator slotter of the class described, a frame, a second frame detachably secured thereto, a bed formed on said second mentioned frame, a carriage slideable on said bed, a supplemental frame pivoted to said carriage for vertical movement, a locking means carried by said carriage and supplemental frame to maintain said supplemental frame in any fixed position, a 95 prime mover carried by said supplemental frame, an arbor journaled in said supplemental frame, washers having restricted movement in one direction carried by said arbor, a compression spring interposed between said washers, said washers and spring permitting longitudinal movement of said arbor, a cutter carried by said arbor having lateral movement in following the lines of insulation on commutators, a link pivoted 100 to said carriage and yieldably connected to said second mentioned frame, and a hand lever pivoted to said second mentioned frame having variable connection with said link.

115 In testimony whereof we affix our signatures in presence of two witnesses.
